UNITED STATES PATENT OFFICE.

RICHARD SYLVESTER, OF WASHINGTON, DISTRICT OF COLUMBIA.

DEVICE FOR DISPLAYING PICTURES, &c.

SPECIFICATION forming part of Letters Patent No. 605,148, dated June 7, 1898.

Application filed October 15, 1897. Serial No. 655,342. (No model.)

To all whom it may concern:

Be it known that I, RICHARD SYLVESTER, a citizen of the United States, residing at Washington, in the District of Columbia, have invented new and useful Improvements in Devices for Displaying Pictures, &c., of which the following is a specification.

My invention relates to an improved device for displaying pictures, advertisements, photographs, and the like; and it has for its object to provide a device of this character which shall afford means for securely storing or filing away such pictures, advertisements, or other matter to prevent observation or molestation thereof when it is undesirable that they should be seen, and which shall also afford ready and convenient means to facilitate handling of the same for observation or reference when so desired.

While my invention, broadly considered, is applicable for use for the purposes to which devices of the character above indicated are generally put, I have nevertheless designed the same especially for use in detective bureaus, police quarters, or, in brief, any place where photographs and records are kept of criminals; my aim being to provide a more convenient means for handling or consulting such photographs or records than now exist. At the police headquarters and detective bureaus of the larger cities of this and other countries a photograph is taken and a record kept of every criminal arrested. This record consists of measurements of various parts of the criminal's body, a memorandum of any peculiar mark he may carry which would tend to distinguish him from others, the color of his eyes and hair, a brief history of the crimes he may have committed, if such are known, and any other matter which would aid in identifying him. This record is usually pasted on the reverse side of the card carrying his photograph, and the whole is filed away for reference. A system of exchange exists between the larger cities of this country, and two photographs, a front and a side view, of a criminal arrested in one city are sent to each of the other cities, together with the record, to be kept for reference. These photographs accumulate by the thousands at the various headquarters, and some better means than

now exists has long been desired which would permit such photographs to be filed away where they would be secure from observation and molestation and be protected from light 55 and dust and at the same time afford a ready means of access for reference when desired.

Having thus outlined the special uses and objects of my invention, I will now proceed to describe the construction of the same in 60 detail, referring to the accompanying drawings, in which—

Figure 1 is a view in elevation of the complete device with the cover removed. Fig. 2 is a plan view showing the cover in dotted 65 lines. Fig. 3 is a side view. Fig. 4 is an enlarged view of a portion of one of the picture-carrying frames. Fig. 5 is a sectional view on the line 5 5 of Fig. 4. Fig. 6 is a view, partly in section, showing my preferred means 70 for supporting the picture-carrying frames in the guide-rails; and Fig. 7 is a like view showing a modification.

The letter A designates the frame of the device, which comprises two boards *a a'*, 75 united at their upper ends by a cross-piece B, forming the top of the device, the parts being suitably shaped and finished to form an ornamental structure designed to be secured in any suitable manner to a wall or other desired backing. Secured to the frame at points near its top and bottom, respectively, are guide-rails C D. These rails extend outward from the frame A for the desired distance and have a slight upward inclination. The rail 80 C has in its under surface a retaining-slot *c*, and the rail D has in its upper surface a similar slot *d*, the purpose of which will be presently stated. The said guide-rails are approximately semicircular in shape, and at 90 their outer central portions are each provided with a curved recessed or depending portion *c' d'*, respectively. As shown, the guide-rails C D carry at their inner ends plates *e e'*, suitably apertured to receive screws *e'*, by which means they are attached to the frame A, and the upper guide-rail C is further braced by means of a rod *a²*, connected thereto and carrying at its inner end a plate *a³*, suitably apertured to receive screws *a⁴*, by which means 95 it is secured to the frame A. It is obvious, however, that other means than those shown

may be employed for securing the guide-rails to the frame without departing from the spirit of my invention.

The letter E designates the picture-carrying frames, which comprise top and side frame-pieces $f f'$, respectively, and extending between the side frame-pieces and at a distance apart about equal to the length of an ordinary cabinet photograph are cross-strips f^2 . The picture-carrying frames E may be made of any desired material; but for the sake of lightness I preferably form them of aluminium. The said cross-strips f^2 and the end frame-pieces f are provided at intervals along their length with clips e^2 , which are provided with a hole to receive a rivet, a two-prong paper-fastener, or other means g for fastening the photographs h to the frame, as will more clearly appear by reference to Fig. 5. At their upper and lower ends the frames E are provided in their central portions with headed projections $E' E^2$, the heads of which are retained and work within the retaining and guide grooves c and d , respectively. When not in use, the frames carrying the photographs are all slid to one side of the frame A and protected from light and dust as well as molestation by an unauthorized person by means of a swing-cover II, (indicated by dotted lines in Fig. 2,) which is provided with suitable locking means.

In practice the frames are all numbered, and an index is kept of each photograph, stating by which frame it is carried. When it is desired to refer to a given frame or if all of them have to be examined, the cover is unlocked and swung aside, the frames are moved along the guide-rails to the opposite side of frame A until the required or any desired frame carrying a photograph of a criminal whose record is to be examined is reached, when the frame is moved till the projections $E' E^2$ reach the recessed portions $c' d'$, respectively, where the frame is, so to speak, held in a fixed position, and being pivotally supported between the guide-rails it may be axially rotated to bring the reverse side of the frame to view, by which means the records k on the backs of the photographs may be consulted.

In Fig. 7 I have shown a modification of the means for supporting the frames between the guide-rails. In this construction the frames E are swiveled to metal housings K K', carrying rollers $r r'$, respectively, which engage the guide-rails C D.

The projections $E' E^2$ do not necessarily have to be moved into engagement with the recessed portions $c' d'$, as the frames may each be rotated at any point on the guide-rails, provided each is removed a sufficient distance from the remaining frames; but said recessed portions form a convenient point at which to turn the frames.

By securing the guide-rails C D to the frame A in such manner that they have an upward inclination I provide at each side of the de-

vice inclined planes which facilitate moving the frames backward against the frame.

As previously stated, while I have designed my device for the special uses above indicated, it is apparent that it is equally susceptible of use by photographers and advertisers in displaying samples, cards, advertising matter, and merchandise. 75

Having thus fully described my invention, what I claim as new, and desire to secure by Letters Patent, is—

1. In a device for displaying photographs and the like, the combination with a frame-support having upper and lower parallel curved guide-rails extending outward therefrom, of frames slidably mounted on said guide-rails, substantially as described. 80

2. In a device for displaying photographs and the like, the combination with a frame-support having upper and lower parallel curved guide-rails, extending outward therefrom, of frames slidably and rotatably mounted on said guide-rails, substantially as de- 85 90

95

3. In a device for displaying photographs and the like, the combination with a frame-support having upper and lower parallel curved guide-rails extending outward and upward therefrom, of frames slidably mounted on said guide-rails, substantially as de- 95

100

4. In a device for displaying photographs and the like, the combination with a frame-support having upper and lower parallel and approximately semicircular guide-rails extending outward therefrom and provided at their outer central portions with recesses, of frames slidably and rotatably mounted on said 105

at one side of the frame-support, substantially as described.

8. The combination with a frame-support having upper and lower parallel guide-rails extending outward therefrom, of frames slidably and rotatably mounted on said rails, comprising side and end frame-pieces, cross-strips extending between said side frame-pieces, apertured clips formed on the end frame-pieces and cross-strips, and means for attaching a

photograph to said clips, substantially as described.

In testimony whereof I have hereunto set my hand in presence of two subscribing witnesses.

RICHARD SYLVESTER.

Witnesses:

JAMES L. NORRIS,
F. B. KEEFER.
